UNITED STATES PATENT OFFICE

FREDERICK E. HOLLINS, OF WINCHESTER, MASSACHUSETTS

CARD GAME ADJUNCT

Application filed July 6, 1932. Serial No. 621,035.

The object of this invention is to provide an improved adjunct for use in card games such as duplicate whist to segregate the card hands that have been played by one group of players, and permit the use of the same hands by another group.

A particular object is to provide an adjunct adapted to be opened to expose the card hands, and compactly folded so that the hands may be stored side by side in an ordinary card case of a size slightly exceeding that of a case intended to contain a pack, or deck of cards.

Of the accompanying drawing forming a part of this specification,—

Figure 1 is a perspective view showing my improved adjunct opened.

Figure 2 is a perspective view showing the adjunct partly closed.

Figure 3 is a fragmentary sectional view on the plane indicated by line 3—3 of Figure 2.

Figure 4 is a perspective view showing the adjunct completely closed and adapted to be stored in a card case.

Figures 5 and 6 are perspective views showing two of the swinging trays herein-after described.

Figure 7 is a fragmentary sectional view on the plane indicated by line 7—7 of Figure 1.

Figure 8 is a perspective view of the tray confiner hereinafter described.

Figures 9 and 10 show parts of the tray confiner in perspective.

Figure 11 is a perspective view showing the adjunct closed and inserted in a card case.

The same reference characters represent the same parts in all of the figures.

The tray confining member shown separately by Figure 8 is oblong and rectangular and is a shallow hollow box.

The preferred confiner includes an oblong frame composed of longitudinal side members 12, and transverse end members 13, said frame being preferably an aluminum casting, a flat bottom which may be cast with the frame, and a flat top piece 16 having parallel beveled edges 17 engaged with beveled

or undercut guides 18 on the upper side of the frame members 12, the top piece being slidable on the frame to and from the operative position shown by Figure 8.

In the mid length portions of the end members 13 are formed slot portions 19 which open into slot portions 20 formed in the top piece 16, and extending obliquely inward, the slot portions 20 having closed ends 21 located at opposite sides of the mid length of the top piece.

The adjunct comprises four trays arranged in pairs, the trays of one pair being designated by 22, and those of the other pair by 23. Each tray is adapted to confine and expose one side of a card hand 24.

Each tray has at its inner end a card hand confining member 25, and at its outer end a slot 26 permitting removal of the card hand by a thumb and finger.

Connections are provided between the confiner and the trays, permitting the trays to lie in the same plane with the confiner, and radiate therefrom as shown by Figure 1, and to be gathered on and upstand from the top face of the confiner, side by side, as shown by Figure 4.

The preferred connections between the trays 22 and the confiner are embodied in the slot portions 19 and 20 in the confiner, and trunnions 29 projecting from the inner ends of the trays 22, said trunnions having heads 30.

The trunnions 29 are inserted in the slot portions 19 when the top piece 16 is moved endwise from the operative position shown by Figure 8, and are prevented from withdrawal by the heads 30 and the top piece when the latter is moved back to said operative position.

The described connections permit the upward swinging of the trays 22, the trunnions moving into the slot portions 20 until they abut the closed ends 21 thereof, and being then partly rotated to locate the trays 22 in the upstanding position shown by Figure 2, the trays 22 being gathered side by side.

The connections between the trays 23 and the confiner are embodied in hinge pintles 32 projecting from the end members 13 of the

confiner, and resilient hinge ears 33 on the inner ends of the trays 23, said ears being sprung onto the pintles 32, so that hinges are provided permitting the upward swinging of the trays 23 until they abut the upstanding trays 22, as shown by Figure 4.

The four trays are thus gathered so that they constitute a compact body adapted to be stored in a card case 35, as shown by Figure 11.

The trays are made of thin sheet metal, and their depth is such that when they are gathered the thickness of the body formed thereby only slightly exceeds the thickness of a pack of cards. The area of the top surface of the confiner corresponds to the aggregate area of the inner ends of the trays when the trays are gathered as shown by Figure 4.

After the described parts are assembled the top piece 16 of the confiner may be rigidly secured in any suitable manner so that it is immovable relative to the frame, for example, a slight indentation may be made by a prick punch in one, or both, of the frame members 12 in such manner as to displace some of the frame metal into notches 38, Figure 9, in the top piece.

I claim:

1. A card game adjunct comprising four trays adapted to separately confine the four hands of a card pack, a rectangular oblong tray confiner having a top face whose area corresponds to the aggregate areas of the inner ends of said trays when they are gathered side by side, and connections between the trays and the confiner permitting the trays to lie in the same plane with the confiner and radiate therefrom, and to be gathered on and upstand from the top face of the confiner side by side, the confiner and the gathered trays constituting a compact body adapted to be stored in a card case.

2. A card game adjunct comprising four trays adapted to separately confine the four hands of a card pack, a rectangular oblong tray confiner having a top face whose area corresponds to the aggregate areas of the inner ends of said trays when they are gathered side by side; connections between two of the trays and the confiner permitting said trays to extend in opposite directions from the opposite end edges of the confiner, and to be gathered on the top side thereof and stand side by side thereon, said connections including headed trunnions on said trays, and guiding slots in the confiner ends and top in which said trunnions are movable and adapted to turn, and hinges connecting the other two trays with the confiner and permitting said trays to extend in opposite directions from the opposite side edges of the confiner, and to be gathered on and upstand from the top face thereof beside the first mentioned trays.

3. A card game adjunct as specified by claim 2, said confiner being hollow and com-

posed of an oblong frame, a bottom piece fixed to the frame, and a top piece engaged with guides on the side members of the frame, the end members of said frame and the top piece being provided with slots in which said headed trunnions are movable and adapted to turn, the heads of said trunnions preventing withdrawal of the trunnions from the slots, the end members of the frame having projecting hinge pintles engaging resilient hinge ears on two of the trays.

In testimony whereof I have affixed my signature.

FREDERICK E. HOLLINS.
